GAME

Arthur J. Jones, Indianapolis, Ind.

Application October 27, 1939, Serial No. 301,522

3 Claims. (Cl. 273—95)

This invention relates to a game and has for a primary object the provision of a structure to play a ball game in which the skill of an operator is required for effective results. The objects 5 and advantages of the invention will become more apparent in the following description of one particular form of the invention as illustrated more or less diagrammatically in the accompanying drawing, in which

10 Fig. 1 is a side elevation in partial view of a device employing the invention;

Fig. 2, a top plan view of the base on a slightly enlarged scale;

15 Fig. 3, a detail in side elevation of the attachment of the ball restraining cord;

Fig. 4, a detail in top plan view of that attachment;

Fig. 5, a side elevation of one form of bat employed, and

20 Fig. 6, a modified form of bat.

Like characters of reference indicate like parts throughout the several views in the drawing.

I form a base 10, herein shown as in the nature of a block. The exact conformation of this 25 block is immaterial but it should be so made that it will remain stationary on the floor or ground or may be buried in the ground. Entering from the top face of the block 10 is a generally conical cavity 11 tapering from a large opening at the top 30 to a smaller bearing surface at the inner lower end. In the form herein shown, this cavity 11 is convoluted as indicated in Fig. 2 so as to provide ridges 12 spaced around the cavity between intervening depressions, the lower end of these 35 depressions tapering out to the central lower bearing surface.

A pole 13 is provided to have its lower end entered in the cavity 11 to have its lower end rest on the bearing surface at the lower end of the 40 cavity. The pole 13 is preferably longer than the height of the average person and will be free to rock in the cavity 11 over to some extreme position as indicated by the dash lines in Fig. 1, which position is limited by the pole striking the 45 side of the cavity 11.

To the upper end of this pole 13 is attached a 50 rope or cable 14 of any suitable material, preferably flexible. The exact nature of the attachment of the rope 13 to the pole 14 is immaterial provided the attachment forms a swivel connection so that the rope 14 is free to travel around the pole 13 without winding up thereon. While the usual swivel may be employed, the form herein shown is workable. As indicated in Figs. 3 and 55 4, the upper end of the pole 13 may be notched

and the rope 14 looped around that notch. The rope 14 is thus connected with the pole but is free to turn therearound and is prevented from slipping longitudinally of the pole.

On the outer end of the rope 14 is carried a 5 ball 15. This ball 15 may be made out of any material desired such as rubber or may even be the usual construction of a baseball. The exact construction of the connection between the rope and the ball 15 is immaterial although it must 10 be quite durable to stand up under the action imparted to it during the playing of the game. In the form herein shown, the ball has a loop 16 secured to it, through which the rope 14 passes to make the connection. As indicated however, the 15 exact form of securing of the rope 14 to the ball 15 does not enter into my invention.

In playing the game, one person will stand near the block 10 and grasp the pole 13 and start 20 swinging it around to have its upper end describe a small circle while the lower end remains seated in the block 10. The idea is to start the ball 15 swinging around the pole 13 with the rope 14 in fully extended position swiveling around the pole 13 without wrapping around it. 25 A number of players will be stationed outside of the path of the ball 15 and each of these players will be equipped with a bat such as is shown in Fig. 5. Each of these players will take turns in 30 trying to strike the ball 15 with the bat but the person operating the pole 13 will use his skill to divert the ball 15 from its true circular path by rocking the pole 13 laterally to jerk the ball over as is indicated in Fig. 1. The pole 13 however is limited in this movement so as to prevent the ball 15 from striking a person on the opposite 35 side of the ring formed by the players around the base 10 outside of the normal path of the ball 15. By providing the recesses in the cavity 11 between the ridges 12, the operator can not swing 40 the pole around in the extreme outwardly tilted position to complete circular travel. The pole 13 must always be brought back to swing the ball around its circular path by swinging the pole 13 within the circle described within the ridges 12. 45 A variation of this game may be had by each player employing a bat of the type shown in Fig. 6 in which case the bat is provided with a hole 17 slightly larger than the ball 15. The player attempts to get the ball 15 through this hole 17. 50

In any event, the rules of the game may be varied without departing from the spirit of the invention particularly in the number of strikes each player may make before he is out and so forth.

While I have herein shown and described my invention in the one particular form it is obvious that structural changes may be employed without departing from the spirit of the invention and I do not desire to be limited to that form beyond the limitations as may be imposed by the following claims.

I claim:

1. In a game, a base having a hole therein of appreciable depth, a pole entering the hole to be rockably supported therein, a ball and a cord swivelly connected to the upper end of the pole and carrying the ball on its outer end, said base hole being formed to receive said pole with a loose fit to permit a wobble motion to be imparted to said pole.

2. In a game, a base having a hole therein of appreciable depth, a pole entering the hole to be rockably supported therein, a ball and a cord swivelly connected to the upper end of the pole

and carrying the ball on its outer end, said hole being generally of an inverted conical shape to have a lower bearing surface for the end of said pole, the depth of said hole being sufficient to support the pole when leaning against a side thereof. 5

3. In a game, a base having a hole therein of appreciable depth, a pole entering the hole to be rockably supported therein, a ball and a cord 10 swivelly connected to the upper end of the pole and carrying the ball on its outer end, said hole being generally of an inverted conical shape to have a lower bearing surface for the end of said pole, the depth of said hole being sufficient to support the pole when leaning against a side thereof, the side wall of said hole being provided with outwardly extending pockets to receive the pole therein. 15

ARTHUR J. JONES. 20
